UNITED STATES PATENT OFFICE

102,404

DESIGN FOR A COMBINED HORN AND LAMP

Lee M. Wiley, Marion, Ind., assignor to Delta
Electric Company, Marion, Ind., a corporation
of Indiana

Application April 1, 1936, Serial No. 61,895

Term of patent 3½ years

To all whom it may concern:

Be it known that I, Lee M. Wiley, a citizen of the United States, residing in Marion, in the county of Grant and State of Indiana, have invented a new, original, and ornamental Design for a Combined Horn and Lamp, of which the following is a specification, reference being had to the accompanying drawing, forming part thereof.

Fig. 1 is a perspective view of a combined horn and lamp showing my new design.

Fig. 2 is a side view thereof.

I claim:

The ornamental design for a combined horn and lamp substantially as shown.

LEE M. WILEY.
